**ELECTRON DISCHARGE DEVICE COMPRISING
AUXILIARY ELECTRODE IN GRID SECTION**
Mehmet Esin Ulug, Etobicoke, Ontario, Canada, assignor
to Canadian General Electric Company, Limited, Toronto, Ontario, Canada, a corporation of Canada
Filed Sept. 28, 1962, Ser. No. 226,997
6 Claims. (Cl. 313—238)

This invention relates to electron discharge devices and more particularly to the improvement of positive grid number three current characteristics in dual control twin pentodes and dual control twin heptodes.

A dual control twin pentode, tube type 6BU8 is discussed in an article entitled, "A New Noise-Gated Automatic Gain Control and Sync System for Television Receivers—Part II," by George C. Wood published in the "IRE Transactions on Broadcast and Television Receivers," dated June 1960, pages 32—34. My invention will be discussed in connection with the above-mentioned tube. A tube using my invention has been registered as a 6BU8A tube. However, the scope of my invention is not limited to this type only. The construction of the 6BU8 tube is unique in that the cathode, grid number one, and grid number two are common to both pentodes. The plate and grid number three are split in half forming two individual plates or sections.

One function of the grid number three of the pentode is to provide a grid leak bias which increases in proportion to the magnitude of the signal voltage between the grid number three and the cathode. The grid leak bias is obtained through diode action of the grid number three as the positive swing of the applied signal tends to drive grid number three into the grid current region.

When the 6BU8 type pentode tube is connected in a circuit and is subjected to very strong signals entering the positive grid region the tube exhibits a defect known as "blocking" and it causes saturation or reversal of grid number three current in the positive voltage region as will be shown in association with the description of FIGURE 3. The defect "blocking" is caused by either the secondary emission of electrons from grid lateral wires or by the potential differences between grid number three and the space charge surrounding it.

Methods to overcome these defects have been employed in the art, such as carbonizing the grid number three laterals, or connecting a grounded electrode (a shield) to the cathode and locating the grounded electrode between grids number two and three, to increase the screen grid dissipation. Neither of these methods have proved completely satisfactory and actually have introduced other objectional disadvantages.

I have found that these disadvantages mentioned above can be overcome by providing an auxiliary electrode in association with one section of grid number three located in close proximity to the cathode and disposed midway between grid number one and grid number two. The electrode forms a triode having grid number one as a control grid and a cathode in common with the pentode section. The grid number one is wound with a variable pitch having the turns of one pitch adjacent the auxiliary electrode and the turns of another pitch along the remaining length of the grid. The triode conducts when the grid number three, to which the electrode is galvanically connected, is positive. When a noise signal or a negative potential appears on grid number one (the control grid), the triode cuts off.

The auxiliary electrode connected to grid number three functions as the plate of a triode when the grid number three is positive to provide a grid leak bias current for grid number three so that grid number three does not ex-

hibit a reversal of current in the positive grid region or premature saturation characteristics. The auxiliary electrode also provides a rapid adjustment of the grid leak bias voltage in response to an increase in the potential of the applied signal.

The positive grid number three current characteristics are improved with my invention without upsetting the negative grid number three characteristics or the noise immunity action of grid number one.

The negative grid number three characteristics are the characteristics displayed by the grid number three under normal operation with negative grid leak bias.

The noise immunity action of grid number one means that grid number one will prevent the electrons from flowing to both plates if a noise signal or a negative signal is applied to it.

The characteristic features of the invention are defined in the appended claims and one embodiment is described in the following specification and shown in the accompanying drawings in which:

FIG. 1 is a top view of a tube type 6BU8A using my invention;

FIG. 2 is a sectional view of the same tube taken on the line A—A of FIG. 1; and

FIG. 3 is a graph showing the positive grid number three characteristics of 6BU8A and 6BU8 tube types.

Referring now to FIG. 1 and FIG. 2 which illustrate a 6BU8A type pentode tube without a base, contact prongs and an envelope which have been omitted, the part between the upper top mount 8 and bottom mount 9 being shown. An anode plate 10 is shown in FIG. 1 (omitted in FIG. 2) which partially surrounds grid number three (6), a screen grid number two (5), a grid number one (3) of which a side rod 7 is shown in FIG. 2, and a cathode 1 which is coated on a cathode sleeve 2. A shield 11 encloses the cathode 1, grid 3 and grid 5. The plate 10 and the grid 6 are split in half, each forming two individual sections. The cathode 1 emits an electron stream which can go in two separate directions and after traversing grid 3 and screen grid 5 may pass through grids 6 to each of the sections of plates 10 providing none of the grids are biased beyond cutoff. My invention comprises an auxiliary electrode 4 which may be termed a triode plate and which is illustrated as being galvanically connected, that is, conductively connected, to one section of the grid 6 in the tube and disposed midway between the grid 3 and the screen grid 5. The section of grid 6 connected to the auxiliary electrode 4 becomes the plate of a triode which has a cathode 1 and control grid that is actually part of grid 3. The part of grid 3 which acts as the control grid of the triode is wound with a pitch which is different from the pitch of the remainder of grid 3 in common with the pentode.

This triode conducts without saturation when the grid 6 is positive and cuts off completely when a noise signal appears on grid 3. The electrode 4, being galvanically connected to the grid 6 improves the grid leak performance of grid 6. That is to say, the current characteristic of grid 6 does not saturate and does not reverse its direction, as will be shown in the description of FIG. 3.

The electrode 4 of FIG. 1 and FIG. 2 is shown in the form of a small metallic plate-like tab located at the top of a mount 8 in close proximity to the cathode 1. The area of the electrode 4 should be of such dimensions that it provides a grid leak bias through diode action of the grid 6 as the positive swing of the applied signal tends to drive grid 6 into grid current region.

In a 6BU8A type dual control twin pentode tube used in a sync separator-clipper and automatic gain control circuit for a television receiver, I have found that a small metallic tab 0.060 inch wide, 2 mm. long, and 0.005 inch

thick galvanically connected to the control grid 6 and located approximately 0.045 inch from the cathode center line, as shown in FIG. 1 and FIG. 2 operates very effectively to overcome the difficulty of slow acting grid biasing of other dual control twin pentode tubes, i.e. the 6BU8 tube. In addition the cathode coating has been extended 1 mm. at the top of mount 8 and seven turns of wire have been removed from grid 5 to provide a triode tube in association with the pentode section. Also, the grid 3 has been wound with a 60 turns per inch pitch adjacent to the auxiliary electrode 4 and a 106 turns per inch pitch along the remainder of its length.

The operation of the grid 6 and the auxiliary electrode associated with it is shown in the graph of FIG. 3. FIG. 3 shows the positive grid number 3 characteristic with voltage (in volts) along the abscissa axis and current (in microamps) along the ordinate axis in which curve 20 shows the positive characteristics of the 6BU8A tube. The characteristic current does not saturate or reverse its direction for the voltage range of 1-60 volts. Curve 21 represents the positive characteristics of the number three grid of a 6BU8 tube. The region A in the curve 21 is a positive grid region and extends normally to a value of about 5 volts. The current saturates around 400 microamps and has a knee at 5 volts. The region B extends from plus 5 volts to about 50 volts and the region C extends from about 50 volts to full plate voltage. Referring to the curves it will be noted that the region B on curve 21 shows a negative slope. This negative resistance or slope is one reason for the difficulty known as "blocking" and when "blocking" occurs the grid is thrown into region B. Once this region B is entered, the grid potential remains in the bottom of the "valley" indicated on curve 21 between regions B and C. It happens that the grid potential in this region is approximately 50 volts and is positive and the grid will remain at a high positive value for a period of time since the amplitude of the current drawn by the number three grid is not enough to charge up a grid leak condenser and restore negative bias. At this high positive grid number three voltage the plate current is only limited by the emission from the cathode and this high current is sufficient to overheat the tube, liberate gas, and destroy the function of the tube, finally causing the destruction of the tube.

It will be apparent from the curve 20 shown that "blocking" will not occur in the 6BU8A tube since the current at 50 volts is around one milliamp and the value of the grid number three current is much larger than usual emission currents from the grid laterals. A 6BU8A type dual control twin pentode will also have the advantage of reducing the grid leak bias resistance required, by a considerable amount without deteriorating the tube's performance at low signal levels. Because of the higher current capabilities of grid number three the lower values of grid leak bias resistance will help to provide long and trouble-free life.

What I claim as new and desire to secure by Letters Patent of the United States is:

1. An electron discharge device comprising, a substantially evacuated envelope enclosing a cathode and anode mounted in spaced position, first, second, and third control grids mounted in a spaced sequence from the cathode to the anode; and an auxiliary electrode conductively connected to said third control grid and positioned in close proximity to the cathode to improve the positive voltage characteristics for said third control grid.

2. An electron discharge device comprising, a substan-

tially evacuated envelope enclosing a cathode and an anode mounted in spaced position, first, second, and third control grids mounted in a spaced sequence from the cathode to the anode; and an auxiliary electrode conductively connected to said third control grid and positioned between said first and second control grids.

3. An electron discharge device comprising, a substantially evacuated envelope enclosing a cathode and an anode mounted in spaced position, first, second, and third control grids mounted in a spaced sequence from the cathode to the anode; and an auxiliary electrode conductively connected to said third control grid, said auxiliary electrode comprising a short metallic plate-like tab extending on one side only of said third control grid and positioned halfway between said first and second control grids.

4. An electric discharge device comprising, a substantially evacuated envelope enclosing a cathode and an anode mounted in spaced position, first, second, and third control grids mounted in a spaced sequence from the cathode to the anode, said first grid being wound with a variable pitch, and an auxiliary electrode conductively connected to said third control grid, said auxiliary electrode comprising a small metallic plate-like tab positioned adjacent to one side of said third control grid and halfway between said first and second control grids, said first control grid having a different pitch adjacent said auxiliary electrode than the pitch for the remainder of the first control grid.

5. A dual control twin pentode tube comprising two pentode sections, a substantially evacuated envelope enclosing a cathode and an anode in each section, said cathode being common to both of the pentode sections of said tube; first and second control grids being common to both of the pentode sections of said tube, said first grid being wound with a variable pitch; a pair of third control grids, one in each pentode section being separated from said first and second control grids and positioned between said second grid and the anode in each section, an auxiliary electrode conductively connected to only one of said third control grids and positioned midway between said first and second control grids in one of pentode section.

6. A dual control twin pentode tube comprising two pentode sections, a substantially evacuated envelope enclosing a cathode and an anode in each section, said cathode being common to both of the pentode sections of said tube; first and second control grids being common to both of the pentode sections of said tube, said first grid being wound with a variable pitch; a pair of third control grids, one in each pentode section being separated from said first and second control grids and positioned between said second grid and the anode in each section, an auxiliary electrode conductively connected to only one of said third control grids and positioned midway between said first and second control grids in one of pentode section, said first control grid having a different pitch adjacent said auxiliary electrode than the pitch for the remainder of the first control grid.
